UNITED STATES PATENT OFFICE.

RICHARD DRURY, OF LIVERPOOL, ENGLAND.

LIFE-BELT.

1,109,907.

Specification of Letters Patent.

Patented Sept. 8, 1914.

Application filed March 17, 1913. Serial No. 754,843.

To all whom it may concern:

Be it known that I, RICHARD DRURY, a subject of the King of England, residing at Liverpool, in the county of Lancashire, England, have invented new and useful Improvements in Life-Belts, of which the following is a specification.

The usual type of life belt consists of a number of cork slabs fitted within canvas pockets, tapes being attached to the extremities of the end pockets for tying so that the belt may be secured to the body, a brace tape being also provided which when in position passes from the front portion of the belt 10 around the neck and is made fast again at the front portion. The tapes which secure the belt to the wearer are sometimes passed around the exterior of the cork pockets before being secured at the front. It is found 15 however when such types of life belts are in use that owing to the exertions of the wearer, say by swimming or rowing the belt slips down beneath the tape and gets out of position, the brace tape being of little 20 value except to support the front portion of the belt which consequently gets very much out of position, becomes very inconvenient and handicaps the wearer. Further in the present types of life belts, the 25 belt unless made a special fit is apt to become too loose, belts being usually made a standard size and that the largest required. According to the present invention the life belt is made of a series of cork slabs in- 30 closed in canvas or like pockets and so ar- ranged that the circumferential length of 35 the belt when in position on the wearer may be contracted by a single pull thus enabling it to fit immediately several sizes of persons.

40 The invention further consists in providing such an arrangement of a single supporting tape by which the belt will be held up at front and back at just the required position on the figure of the wearer to insure freedom of action.

The invention is illustrated in the accompanying drawings in which:—

Figure 1, is a perspective view showing the life belt in its extended position; Figs. 50 2 and 3 are views showing the belt fitted and in use on the person.

In carrying out the invention the belt is preferably made of canvas or other textile material (1) formed into a number of pockets (2) each pocket being fitted with a slab 55 of cork, the slabs being longer at the ends

and middle of the belt as in the usual manner. In the center of the belt corresponding to what is the back of the belt when in position on the wearer, a space (3) of several inches of canvas is left between the adjoining pockets and a space of about an inch or so is also left between the remaining pockets. These spaces are to provide for the cork slabs and pockets being pulled 60 up closer together and the circumferential length of the belt decreased to adjust it to different sizes.

All the pockets excepting the outer or end ones 2^a are fitted on their exterior surfaces 70 with tabs or yoke-pieces 4, say of stout webbing or the like material, beneath which the binding or adjusting tapes 5, 6, are passed. There are superposed two such binding tapes, secured to opposite end pockets of the 75 belt and then passed beneath all the tabs on the pockets. To fit the belt on the wearer it is put on in the usual way, the free ends of the binding tapes being then passed around hooks 7 and 8 or the like abutments fitted to 80 the exterior surface of the end pockets, the tapes being, preferably, threaded around the hooks in such a manner that the free end of the tape coming around the right side of the belt is passed over the hook on the left side 85 of the belt, and vice versa, see Fig. 2. By drawing the free ends of the tapes around the hooks the whole belt will be tightly contracted and fitted about the person, the free ends of the tape being tied after such adjustment.

The brace strap 9 is connected up at one end 9^a permanently to the upper edge of one outer pocket, threaded through an eye 10 in the center or rear of the belt, and detachably coupled by means of a hook 11 and eyes 12 in the strap to the upper edge of the other outer pocket. The disposition of this yoke strap, when in use, is from the breast of the wearer over one shoulder, through the eye 100 at the back and returning over the other shoulder to the breast. The detachable end of the brace tape is fitted with a succession of eyes or rings 12, so that by pulling on this tape it may be drawn and tightened up one or more rings, and in this way 105 the height of the belt on the wearer adjusted as required.

If desired the front hooks 7 and 8 on the end pockets may be dispensed with. These 110 hooks may be of any desired construction, but in order to enable them to lie flat against

the end pockets they are preferably made as shown, the hooks 7, 8, being pivotally mounted in the plates 7^A, and 8^A, secured to the end slabs of the belt; and in order to enable the tapes to lie evenly one on the other, one of them 6 is forked at 6^A where it is attached to the end pocket, the other tape 5 thus passing freely out of the fork as shown to the right of Fig. 1.

10. Such a construction of belt permits of it being readily adjustable to the girth of the wearer, obviates any possibility of the cork slabs slipping from beneath the binding tapes, and by means of the brace strap secures the belt at any determined height on the wearer so that it cannot be displaced by movement or exertion on his part.

Copies of this patent may be obtained for five cents each, by addressing the "Commissioner of Patents, Washington, D.C."

I claim:

A life belt consisting of canvas pockets, with intervening pliable portions and cork slabs in said pockets, and of two superposed straps fixed to opposite ends along the middle of the life belt, open scroll-hooks fixed adjacent to the attached end of each strap in combination with a single shoulder strap fast at one end and adjustably secured to the other end of the life belt with slidable connection at the middle of the life belt, as shown and described.

RICHARD DRURY.
